UNITED STATES PATENT OFFICE.

CHARLES W. WHITE, OF KEWANEE, ILLINOIS, ASSIGNOR TO THE BOSS MANUFACTURING COMPANY, OF KEWANEE, ILLINOIS, A CORPORATION OF ILLINOIS.

GLOVE.

Application filed June 11, 1921. Serial No. 476,697.

To all whom it may concern:

Be it known that I, CHARLES W. WHITE, a citizen of the United States, residing at Kewanee, in the county of Henry and State 5 of Illinois, have invented certain new and useful Improvements in Gloves, of which the following is a specification, reference being had therein to the accompanying drawing.

My invention relates to new and useful 10 improvements in a glove and more particularly to a working glove of the gauntlet type, the principal object residing in protecting the palm and fingers with a covering of leather or similar material. 15 Another object consists in so cutting and securing the material forming the protecting covering as to cover the entire palm of the glove as well as the front, sides, back and crotch surfaces of the fingers. 20 A further object consists in constructing both the body of the glove as well as the protecting covering from blanks cut in a novel manner so that it is only necessary to use a comparatively few parts which are so connected by stitching that the seams will be in 25 such positions as to cause no discomfort to the wearer.

With the above and other objects in view which will appear as the description proceeds, my invention consists of the novel details of construction and arrangement of parts, described in the following specification and illustrated in the accompanying drawings, and while I have illustrated and 35 described the preferred embodiments of my invention it will be understood that such changes may be made as will fall within the scope of the appended claims.

In the drawings:

40 Figure 1 is a plan view of the glove with all parts assembled.

Fig. 2 is a back view of the glove with all parts assembled.

45 Fig. 3 is a plan of the cloth blank for the palm, first finger, thumb, and fronts of the second, third and fourth fingers.

Figs. 4, 5 and 6 are the cloth blanks for the backs of the second, third and fourth fingers respectively, the reduced extensions 50 forming the back of the body of the glove.

Fig. 7 is a plan of the leather covering for the palm, first finger, the fronts of the second, third and fourth fingers and a portion of the thumb.

55 Figs. 8, 9 and 10 are the leather blanks for

forming the coverings for the backs of the second, third, and fourth fingers respectively, and

Fig. 11 is the leather blank for the outer face of the leather thumb. 60

In carrying out my invention, the body of the glove is made of cloth of any suitable character, and the leather covering is connected thereto by stitching or any other suitable manner. 65

In Fig. 3 I have shown the cloth blank for making the palm, first finger, thumb and fronts of the second, third and fourth fingers, 1 indicating the palm portion, 2 the thumb piece, 3-3' the portions for the first finger, and 4, 5 and 6 the fronts of the second, third and fourth fingers, respectively. To form the first finger the outer portion 3' will be folded back on the line 7. The thumb piece 2 will be folded back on the line 8. 70 In Figs. 4, 5 and 6 I have shown the cloth blanks 9, 10 and 11 for the backs of the second, third and fourth fingers, respectively, the reduced portions 12, 13 and 14 forming the back of the cloth body of the 75 glove as more clearly illustrated in Fig. 2. 80

Figure 7 shows the leather blank for the protecting covering for the palm, first finger, the fronts of the second, third and fourth fingers, and a portion of the thumb. 85

The palm covering is indicated at 15, the covering for the fronts of the second, third and fourth fingers at 16, 17 and 18, respectively, and the covering for the first finger at 19-19', the portion 19' being adapted to 90

be folded back on the line 20. The thumb piece is shown at 21 and is adapted to be folded back on the line 22. The leather 95

covering for the backs of the second, third and fourth fingers are illustrated at 23, 24 and 25, respectively, in Figs 8, 9 and 10, respectively, and these will be secured to the 100

finger front portions 16, 17 and 18, the portions 23, 24 and 25 being of such width that they will form not only the back coverings, but the side coverings, the seams formed being towards the front of the glove, not between the fingers, as more clearly shown at 105

26 in Fig. 1. The portion 19' of the first finger covering is also of such width that it will form the seam 27 towards the front of the finger. The outer leather thumb piece is shown at 28, Fig. 11, and will be secured to the leather thumb portion 21. It will be 110

noted by referring more particularly to Fig.

1 that the leather coverings extend down into and protect the crotch surfaces. A gauntlet 29 is secured to the lower edge of the glove, said gauntlet preferably being 5 of canvas or other similar material.

In assembling the parts, the leather finger portions 23, 24 and 25 are connected to the cloth finger portions 9, 10 and 11, respectively, by stitching, preferably at the upper 10 ends, and the side edges of the extensions 12, 13 and 14 of the cloth finger portions will be stitched together to form the back of the cloth body. These combined finger pieces are then connected to the back of the leather 15 blank illustrated in Fig. 7, covering the finger portions 16, 17 and 18 thereof, the leather portions being face to face. The cloth blank illustrated in Fig. 3 is then placed over the top of the leather blank illustrated in Fig. 7 and the thumb portions folded on the lines 8 and 22 with the first finger portions folded on the lines 7 and 20. The leather thumb portion 28 is then connected to the thumb portion 21. The parts 25 are all secured by stitching and the glove is then reversed so as to bring the parts in the positions shown in Figs. 1 and 2. The cloth parts may be connected to the leather parts by stitching around the edges or merely 30 at the ends. While this is the preferable manner of connecting the cloth and leather portions, they may be connected in any other desired manner, the main object of the invention residing in the protecting covering 35 of leather for the cloth portion.

From the above it will be noted that I have formed the glove of comparatively few parts so connected that the seams will not be between the fingers to cause discomfort 40 to the wearer. At the same time the palm and the fingers are each protected by the leather covering, such covering enclosing the fronts, backs and sides of the fingers and protecting the crotch surfaces. A glove of the character described is particularly adapted for workman, the leather covering prolonging the life of the glove as well as protecting the hand. I wish to emphasize the fact that the fingers are entirely covered

and protected throughout their length and 50 circumference.

Having fully described my invention what I claim as new and desire to secure by Letters Patent is:

1. A glove made of cloth and having a 55 protecting covering for the palm and fingers, said protecting covering comprising a palm having finger portions formed integral therewith and separate finger portions adapted to be secured to the integral finger portions to 60 entirely enclose the fingers of the glove, the seams formed by securing the separate finger portions to the integral finger portions being at the front of the fingers.

2. A glove made of cloth and having a 65 protecting covering for the palm and fingers, said protecting covering comprising a palm having finger portions integral therewith, one of said finger portions being of greater 70 width than the others whereby it will be folded to enclose the first finger of the glove, the other finger portions covering the fronts 75 of the glove fingers, and separate finger portions adapted to be secured to the integral finger portions covering the front of the 80 fingers, for enclosing the glove fingers, the seams formed by the folding of that portion forming the first finger and the securing of the separate finger portions to the integral finger portions being at the front of the 85 fingers.

3. A glove made of cloth and having a 85 protecting covering for the palm and fingers, said protecting covering comprising a palm having finger portions formed integral therewith and separate finger portions adapted to be secured to the integral finger portions to 90 entirely enclose the cloth fingers of the glove, each of said separate finger portions being formed of a single piece of material connected to the integral finger portions in such a manner that there will be no seams at the back portions of the fingers above the lowermost points of the separate finger portions.

In testimony whereof I hereunto affix my 95 signature.

CHARLES W. WHITE.
